Inventor:

Berthold A. Lange,

By Hugh K. Wagner,

Attorney.

UNITED STATES PATENT OFFICE

BERTHOLD A. LANGE, OF ST. LOUIS, MISSOURI

BOX JOINT

Application filed December 12, 1927. Serial No. 239,476.

This invention relates to joints or seams for the edges of boxes formed of pasteboard, fiber board, laminated board, and similar material; and pertains more particularly to improvements on the forms of box-joints disclosed in applicant's prior Patent 1,415,368 and his prior application, Serial 32,642. The joints of the said patent and the said application are formed on a definite line 10 and can not be shifted therefrom and moreover provide a reinforcing or bracing portion along the line of the crease. The joint of the said patent allows the material to be bent inwardly, or so as to close the seam, 15 until the flaps on either side of the joint are disposed at right angles to one another; and the joint of the said application permits the material to be folded at right angles and, also, one hundred and eighty degrees 20 inwardly.

The present invention contemplates the provision of a joint that not only presents a definite line on which the flaps can be folded inwardly at right angles, but that, 25 also, allows the flaps to be folded outwardly against themselves or one hundred and eighty degrees. Such an outwardly foldable seam is of use, for instance, where the covering flaps of an erected box that are 30 disposed around the opening thereof must be folded back to allow the box to be filled or emptied. The invention, also, aims to provide a joint of the character described in which the flaps will be braced by a reinforcing portion when they are folded inwardly 35 at right angles. Other objects and advantages will be apparent during the course of the following description of a preferred embodiment of the invention.

40 In the accompanying drawing forming part of this specification, in which like numbers of reference denote like parts wherever they occur,

Figure 1 shows a sheet of laminated paper 45 board being creased by a die to produce the seam of this invention;

Figure 2 is an end view of the sheet of material as it appears after having been withdrawn from the die;

50 Figure 3 is an end view of the material

showing the appearance of the seam or joint after the material has been folded outwardly upon itself thereon;

Figure 4 is an end view of the material as it appears after having been bent inwardly 55 with the flaps on either side of the seam disposed at right angles to one another;

Figure 5 is an end view depicting the flaps folded outwardly one hundred and eighty 60 degrees;

Figure 6 is a fragmentary end view exhibiting the relation of overlapping flaps to the joint after the blank of material of Figure 7 has been folded into box formation; 65

Figure 7 is a plan view showing a box blank that has been creased to provide the joint of this invention; and

Figure 8 is an end view of the box blank 70 of Figure 7.

After the sheet of material 1 has been creased between male and female die members 2 and 3, respectively (Figure 1), and removed therefrom, it presents the appearance exhibited in Figure 2. The material 75 is then bent outwardly on the joint upon itself and then back again, causing it to take the form shown in Figure 3. It will be observed that the seam or joint is U-shaped in cross-section, or of channel formation, the channel comprising an intermediate web portion 4 and flange portions 5 and 6 that connect the web portion 4 to respective flaps 7 and 8 on either side of the seam. The internal corners 9 and 10 80 that are included between the web 4 and the respective flanges 5 and 6 are sharp, as are the internal corners 11 and 12 that are included between the flanges 5 and 6 and their respective adjoining flaps 7 and 8. The flange portion 6 is shorter than the flange portion 5, and is, therefore, not as flexible as the latter, since the layers of the material are not loosened from one another to the same extent in flange 6 as they are in flange 85 5 by the upsetting action of the die. When, therefore, the flaps 7 and 8 are bent inwardly to the position shown in Figure 4, the bending will be definitely localized about the corner 9 as an axis. The web portion 4 90

95

100

is preferably flat and of such width that the adjacent shoulder 13 of flap 7 fits against the bottom face 14 of the channel and completely closes the latter when the flaps are folded as in Figure 4. In this position, 5 also, the shoulder 15 of flap 8 abuts against the inner face 16 of flap 7. The said shoulders function to brace the flaps 7 and 8 against being closed further than their right-angle positions. Moreover, by reason 10 of the bending of the material about the internal corner 9 as an axis, the excess or bulge of material 17 produced by the bending action occurs on the outside of the box; and this effect, together with the interfitting 15 and dovetailing of the adjacent parts on the inner side of the corner, enables the presentation of continuous inner plane surfaces 16 and 18 substantially at right angles to each other. 20

When the flaps are folded outwardly, the bending occurs about the corners 11 and 12 as axes, as shown in Figure 5.

Figures 7 and 8 exhibit the joints of this 25 invention embodied in a box blank comprising an inner row of flaps 19, 20, 21, 22, and 23, and respective outer rows of flaps 24, 25, 26, 27 and 28, 29, 30, and 31. When the blank is folded into box formation, the adjacent outer flaps can not be in the same plane, but must overlap, as will be understood by those skilled in the art. It will be observed in Figure 6 that the adjacent flaps 26 can not bend about the corner 10 as an 30 axis, even though flap 27 tends to push flap 26 toward the right. The material of flap 27 at corner 9 yields sufficiently, however, to allow the lower edge of flap 26 to enter the channel of the joint. It will, therefore, be observed that the longitudinal seams 32 of the blank of Figure 7 may be continuous, and need not be staggered alternately at successive adjacent outer flaps to enable the flaps to overlap when folded.

45 While all the features of this invention are believed to be combinatively novel, certain of the features are manifestly, also, capable of individual use, without the co-operation of other features of the invention. For instance, without departing from the spirit of the invention, the bottom 14 of the channel may be wider than in the specific form shown in the drawing, so that the shoulder 15 of flap 8 does not abut 50 against the face 16 of flap 7.

Having thus fully described this invention, I hereby reserve the benefit of all changes in form, arrangement, order, or use of parts, as it is evident that many minor 55 changes may be made therein without departing from the spirit of this invention or the scope of the following claims.

I claim:

1. A sheet of material having a seam of 60 channel formation comprising an inter-

mediate web portion and flange portions that connect the web portion of the channel to respective flaps on either side of the seam, the dimensions of the channel being such that, when the flaps are folded at right angles so as to close the channel, one of the flaps defines a shoulder that abuts against the inner surface of the other flap to define flaps presenting continuous inner plane surfaces substantially at right angles to each other. 70

2. A sheet of material having a seam of channel formation comprising a flat intermediate web portion and flange portions that connect said flat web portion to respective flaps on either side of the seam, said web portion having its inner surface equal in width to the height of the inner side of one of the flanges so that said side completely closes said channel when the flaps are 80 folded. 85

3. A sheet of material having a seam of channel formation comprising an intermediate web portion and flange portions that connect the web portion of the channel to respective flaps on either side of the seam, the dimensions of the channel being such that, when the flaps are folded at right angles so as to close the channel, one of the flaps defines a shoulder that abuts against the inner surface of the other flap to brace the flaps against further closing. 90 95

In testimony whereof I hereunto affix my signature.
